UNITED STATES PATENT OFFICE.

FRANK H. HEITGER, OF INDIANAPOLIS, INDIANA, ASSIGNOR TO HEITGER CARBURETOR COMPANY, OF INDIANAPOLIS, INDIANA, A CORPORATION OF INDIANA.

CARBURETER.

1,134,531.

Specification of Letters Patent.

Patented Apr. 6, 1915.

Application filed June 8, 1912. Serial No. 702,612.

To all whom it may concern:

Be it known that I, FRANK H. HEITGER, a citizen of the United States, residing at Indianapolis, Marion county, and State of Indiana, have invented and discovered certain new and useful Improvements in Carbureters, of which the following is a specification.

My said invention consists in certain improvements in the details of construction of carbureters for internal combustion engines, especially of the class designed for use on motor cycles and automobiles, whereby the valve for controlling the auxiliary air supply to the mixing chamber may be held under a tension adjusted to suit the requirements of the conditions under which the engine is operating, as to atmosphere, temperature, etc., which tension may be quickly 15 and conveniently changed or adjusted to suit changed conditions, all as will be hereinafter more fully described and claimed.

Referring to the accompanying drawings which are made a part hereof and on which 25 similar reference characters indicate similar parts, Figure 1 is a side elevation of a carbureter embodying my said invention, Fig. 2 a central vertical section through the top portion thereof, Fig. 3 a top or plan view, 30 Fig. 4 a perspective view showing the regulating valve separately for auxiliary air supply, and Fig. 5 a view showing a modification in the construction.

In said drawings the portions marked A 35 represent the casing or body of the mixing chamber, B the float chamber or gasoline reservoir and C the main or hot air inlet thereto.

The main structure of the carbureter 40 shown is of the form in common use known as the Heitger carbureter but may be of any approved form or construction and requires no special description except in so far as it is modified by my present invention.

45 The casing A contains the mixing chamber, the mixture coming into same in the usual manner through suction tube 25. Said casing is provided with an "air cage" a for the auxiliary air inlet and a mixture 50 outlet a¹.

The auxiliary air inlet through the air cage a is controlled by a valve 10 mounted upon the inner end of a torsional spring 11, the opposite end of said spring being made 55 fast to a rock-shaft 12, which is journaled

in suitable bearings in the sides of a hollow lug 17 on the top of casing A. Said rock-shaft projects through the sides of said lug and on one end and has a lever 13 mounted rigidly on one outside end by which it may 60 be turned. Said lever 13 depends from said shaft 12 and near its lower end engages with a toothed segment 14 on the adjacent side of casing A. Said segment 14 is formed with projecting points 15 and 16 at 65 its respective ends which serve to limit the swing of said lever 13. The teeth in said segment are of the form best shown in Fig. 3 and adapted to hold said lever against any backward movement by the horizontal right- 70 angular faces which engage with the rear edge of said lever, while their tapered faces permit said lever to be swung forward by merely pushing from the rear side.

As will be readily seen the tension of the 75 spring 11 tends to hold valve 10 to its seat against the inner end of air cage a of said casing A normally keeping the auxiliary air inlet closed. The spring 11 will yield under any air pressure against valve 10 80 caused by internal suction sufficient to overcome its tension, permitting said valve to open and air from the outside to pass in through air cage a to said mixing chamber. By turning lever 13 in a direction to wind 85 up spring 11, its tension is increased and the valve is held to its seat under greater pressure while when turned in the opposite direction the spring is unwound and its tension decreased, permitting said valve to open 90 under lesser pressure. Thus, where a smaller quantity of air is desired in the mixture, the operator by throwing lever 13 backward increases the tension of the spring 95 and decreases the quantity of air admitted while when a larger quantity is desired the operator withdraws lever 13 away from the segment 14 sufficiently to disengage its edge from the notches therein and swings it forward to secure the tension desired. The 100 square or horizontal front face of the respective notches insures that the lever will be securely held against the internal suction, or vacuum, in the chamber and only moved when forcibly released as above described. 105 A lug 18 is cast on the interior of casing A in position to limit the inward swing of valve 10 at the point desired.

In Fig. 5 I have illustrated a modification by which the lever 13 may be operated from 110

any point, as the front seat of an automobile, through the medium of a connecting rod 20, pivoted thereto and extending to an operating lever or handle conveniently located adjacent to the point desired. A set-screw 5 21 is arranged to limit the normal low tension of the spring and the backward movement of lever 13 will be held by the locking of said operating lever by any common 10 means, not shown.

Having thus fully described my said invention what I claim as new and desire to secure by Letters Patent is—

A carbureter comprising a mixing chamber having an auxiliary air inlet and a hollow lug extending outwardly at one side of 15 said air inlet formed with bearings in its sides for a rock shaft, a rock shaft mounted in said bearings, a helical spring mounted around said rock shaft within said hollow 20 lug with its inner end rigidly attached to said rock shaft and its other end projecting

to a point beyond the center of the auxiliary air inlet, a valve composed of rigid material mounted on the extending end of said 25 spring with its outer face adapted to bear against the inner edge of said auxiliary air inlet for closing the same, a crank arm mounted on one end of said rock shaft outside of said lug, and means for adjusting 30 said crank arm and securing it in different adjusted positions, whereby the tension of said spring may be varied during operation to suit the requirements of the carbureter under varying conditions, substantially as 35 set forth.

In witness whereof I have hereunto set my hand and seal at Indianapolis, Indiana, this twenty-first day of May, A. D. nineteen hundred and twelve.

FRANK H. HEITGER. [L. s.]
